DESIGN FOR A NIGHT LIGHT

James P. Endsley, Sunnyvale, Calif.

Application October 22, 1945, Serial No. 123,083

Term of patent 7 years

(Cl. D48—20)

To all whom it may concern:

Be it known that I, James P. Endsley, a citizen of the United States, residing at Sunnyvale, in the county of Santa Clara and State of California, have invented a new, original, and ornamental Design for a Night Light, of which the following is a specification, reference being had to the accompanying drawing, forming part thereof.

Figure 1 is a top plan view of a night light, showing my new design.

Figure 2 is a front elevational view of the same. The fluted portion is translucent and inclined and square portions of the lamp opaque.

I claim:

The ornamental design for a night light, as shown and described.

JAMES P. ENDSLEY.
